W. WOMACK,

TOOL

APPLICATION FILED SEPT. 27, 1919. RENEWED JAN. 3, 1921.

1,368,085.

Patented Feb. 8, 1921.

William Womack
INVENTOR.

BY

Victor J. Evans

ATTORNEY.

UNITED STATES PATENT OFFICE.

WILLIAM WOMACK, OF EMMETT, IDAHO.

TOOL.

1,368,085.

Specification of Letters Patent. Patented Feb. 8, 1921.

Application filed September 27, 1919, Serial No. 326,903. Renewed January 3, 1921. Serial No. 434,842.

To all whom it may concern:

Be it known that I, WILLIAM WOMACK, a citizen of the United States, residing at Emmett, in the county of Gem and State 5 of Idaho, have invented new and useful Improvements in Tools, of which the following is a specification.

This invention relates to a tool or vise for supporting work, and has for its primary object to provide a tool, which may be efficiently used with work of irregular outline.

An object of the invention is to provide means for supporting two vises in a manner that the latter may assume numerous angular positions.

Besides the above, my invention is distinguished in the manner of connecting the vises to the base, so that the former may 20 be clamped in a plurality of angular positions.

With these and other objects in view the invention will be better understood from the following description, taken in connection with the accompanying drawings, wherein:

Figure 1 is a side elevation of the vise.

Fig. 2 is a longitudinal sectional view.

Fig. 3 is a cross sectional view.

Fig. 4 is a detail view.

Fig. 5 is a plan view of a portion of the turn table.

Fig. 6 is a view of the wrench to be used with my invention.

Again referring to the drawings illustrating one of the many forms in which my invention may be constructed, the numeral 1 designates the base of T shape formation in cross section so as to have the proper 35 sliding action with a pair of clamps 2. Each clamp is adjusted toward and away from the other by a screw 3 mounted in the base and having its head arranged to be readily engaged by the wrench shown in

Fig. 6. Each clamp is constructed of two parts 4 and 5. The part 4 has a slidable connection with the base while part 5 is supported by part 4. The parts are clamped together by a bolt 6, and for the purpose 45 of materially reinforcing this connection part 4 is provided with lugs 7 arranged on opposite sides of the part 4. Each part is formed with a circular depression 8 which co-operates to form a socket 9 for the reception of a ball 10 on the vise 11. This vise

11 comprises a track or base 12 and a pair of jaws 13 adjusted by the screw 14. Mounted in one of the jaws is a set screw 15 which binds the jaw in engagement with the track so that only one jaw will move in the rotation of the screw. Jaw 16, which has mounted therein, the set screw 15, is constructed of two parts 17 and 18 having a swivel connection 19 with each other, so that part 17 may assume a plurality of angular positions. To complete my invention I provide a turn table 20 for supporting the base 1.

From this arrangement it will be seen that each vise may be swung to a plurality of angular positions, so as to effectively engage the work to be acted upon. The construction of the clamp and its association with the vise is such that a vise may be thrown to an angular position and clamped 75 in such position by tightening the bolt 6. In practice this universal connection between the vise and base has a number of advantages, only a few of which have been stated. 80

It is of course to be understood that the invention may be constructed in various other manners and the parts associated in other relations, and therefore I do not desire to be limited in any manner except as 85 set forth in the claim hereunto appended.

What I claim is:—

In a means for supporting a vise, whereby the vise may be arranged at various angles with respect to its support; the combination with a vise having a ball projecting from the base thereof, a support comprising a member having a reduced upper end which is formed on its inner face at its inner corner with an approximately semi-spherical socket to receive the ball therein, a second member resting on the shoulder of the reduced end of the first mentioned member and having its inner face at its inner corner provided with an approximately 90 semi-spherical socket in which the ball is also arranged, lugs on the lower and inner corners of the second mentioned member contacting with the sides of the reduced extension of the first mentioned member, and 100 adjustable clamping means passing through both of the members. 105

In testimony whereof I affix my signature.

WILLIAM WOMACK.
